UNITED STATES PATENT OFFICE.

JOSEPH S. RASNICK, OF ST. PAUL, VIRGINIA, AND WALKER S. BLEVINS, OF KINGSPORT, TENNESSEE.

AIR-BRAKE CONTROL.

1,388,483.

Specification of Letters Patent. Patented Aug. 23, 1921.

Application filed May 26, 1921. Serial No. 472,678.

To all whom it may concern:

Be it known that we, JOSEPH S. RASNICK and WALKER S. BLEVINS, citizens of the United States, residing at St. Paul and 5 Kingsport, respectively, in the counties of Wise and Sullivan, States of Virginia and Tennessee, respectively, have invented a new and useful Air-Brake Control; and we do hereby declare the following to be a full, 10 clear, and exact description of the invention, such as will enable others skilled in the art to which it appertains to make and use the same.

The invention relates to controlling devices for air brakes and has for its object to provide means whereby the air brakes of a train will be set when any of the wheels of the train leave the rails.

A further object is to provide valves located adjacent the wheel flanges and carried by pipes in communication with the air line, said valves having members adapted to engage the rail of the track when the wheel or wheels leave said track and open said 25 valves, consequently causing the brakes of the whole train to be set.

A further object is to provide a train air line with outwardly extending branch pipes, said branch pipes terminating in flexible 30 pipe connections with vertically disposed pipes carried by the stuffing boxes of the car trucks, said vertically disposed pipes having their lower ends inwardly extending and provided with valves disposed within the dished portions of the wheels, and provided with operating levers extending outwardly 35 and positioned to engage the rails when any of the wheels leave the rails, thereby causing the brakes to be set throughout the 40 train.

A further object is to provide the downwardly extending boxing supported pipes with a weakened portion and with a horizontally disposed arm, which arm when 45 forced into engagement with the rail causes the weakened portion to be broken or ruptured thereby allowing exhaust of air from the pipe line.

With the above and other objects in view 50 the invention resides in the combination and arrangement of parts as hereinafter set forth, shown in the drawings, described and claimed; it being understood that changes in the precise embodiment of the invention 55 may be made within the scope of what is

claimed without departing from the spirit of the invention.

In the drawings:

Figure 1 is a side elevation of a portion of a car, showing the device applied thereto. 60

Fig. 2 is a transverse sectional view taken on line 2—2 of Fig. 1.

Fig. 3 is a detail sectional view of a modified form of rail engaging member.

Referring to the drawings, the numeral 1 65 designates a portion of a conventional form of railway car, and 2 the air brake line for controlling the air brake, which air line and the air brake system controlled thereby is so constructed that when the pressure within 70 the air system is lost, for instance by breakage of the air line or by opening the valve, brakes will be set.

Extending downwardly from the air line pipe 2 at a point substantially over each 75 truck is a pipe 3, to the lower end of which pipe is secured outwardly extending pipes 4. The pipes 4 terminate in longitudinally disposed branch pipes 5, to the ends of which are secured in any suitable manner flexible 80 pipe sections 6 which arch over the wheels 7 of the truck and are supported above said wheels by means of brackets 8. The brackets 8 hold the flexible members 6 spaced from the wheels so that said flexible members 85 will not be damaged by contact with the wheels. The flexible members 6 are formed from rubber hose or any other flexible material and have their outer ends connected as at 9 to vertically disposed pipes 90 10 which are secured to the grease boxes 11 by means of straps 12. The grease boxes 11 are carried by the truck of the car and have journaled therein the bearings of the axle. It is obvious that as the body of the car 95 rocks that the pipe sections 10 will move independently of the pipe sections 4 for the reason that the flexible pipe connections 6 will flex.

The lower ends of the pipes 10 extend inwardly and downwardly and have their downwardly extending portions disposed within the chambers 13 of the car wheels 7, thereby so positioning the discharge ends of the pipe that they will not come into engagement with obstructions along the road bed, and at the same time utilizing the shape of the car wheels 7 for protecting the valves 14 which are carried by the lower ends of the pipes 10. The valves 14 comprise casings 110

15, in which casings are pivotally mounted on pins 16 bell crank levers 17. The arms 18 of each bell crank lever 17 extends upwardly and normally closing the air discharge pipe 19. Levers 17 are preferably frictionally held in any position to which they may be moved and when in closed position as shown in Fig. 2 have their arms 18^a extending outwardly from the outer faces 10 of the wheels and substantially horizontally disposed. It will be seen that when any of the wheels on either side of the cars of the train leaves the track, the outwardly extending arms 18^a will come into engagement with 15 the rail of the track and rock the bell crank lever 17. When the bell crank levers 17 are rocked the discharge ports 19 will be opened which will allow loss of pressure in the train line 2 and consequently cause the brakes 20 throughout the train to be set, thereby bringing the train to a stop.

Referring to the modified form of discharge pipe shown in Fig. 3, it will be seen that the end 10^a of the pipe 10 is provided 25 with a cap 20 having a chamber 21 therein, and that said cap is provided with an outwardly extending integral arm 22, which arm when forced into engagement with the rail as the wheel leaves the rail will be forced 30 upwardly, thereby breaking the cap transversely at the reduced portion 23, consequently allowing the escape of the air and setting of the brakes throughout the train. It is to be understood that either form of air 35 release may be used as desired. After the air has been allowed to exhaust and the brakes have been set, if it is desired to again control the brakes, valves 24 may be closed adjacent the exhausting ports 19.

The device has been shown applied to all 40 four wheels of a truck, however, it is to be understood that any number of device may be utilized as desired, that is valves may be located adjacent one wheel or on each side of the truck or at diagonally opposite positions. It will be seen that a device is provided which is simple in construction and one wherein the parts have been reduced to a minimum. It will also be seen that by providing a frangible member that after the 45 cap 20 has been broken at 23 that danger of the valve becoming closed again will be obviated.

The invention having been set forth what is claimed as new and useful is:—

The combination with a railroad car having an air brake pipe and supported on wheels disposed on rails, of outwardly and downwardly extending pipes carried by the air line pipe, flexible connections in said 55 outwardly and downwardly extending pipes, the lower ends of said outwardly and downwardly extending pipes being disposed within the outer chambers of the wheels, valves carried by the outwardly and downwardly 60 extending pipes and means carried by the ends of the outwardly and downwardly extending pipe and so constructed that when it engages the rails air from the train line 65 pipe will be released.

In testimony whereof we have signed our names to this specification in the presence of two subscribing witnesses.

JOSEPH S. RASNICK.
WALKER S. BLEVINS.
